UNITED STATES PATENT OFFICE.

HENRY C. BRAMKAMP, OF SAN JOSE, CALIFORNIA.

NON-REFILLABLE BOTTLE.

1,123,987.

Specification of Letters Patent.

Patented Jan. 5, 1915.

Application filed April 25, 1914. Serial No. 834,468.

To all whom it may concern:

Be it known that I, HENRY C. BRAMKAMP, a citizen of the United States, residing at San Jose, in the county of Santa Clara and State of California, have invented certain new and useful Improvements in Non-Refillable Bottles, of which the following is a specification.

This invention relates to non-refillable bottles and has for its object to provide a bottle wherein any attempt to fraudulently refill the same will be frustrated.

Another object of the invention is to provide a novel means for filling the bottle and sealing the same to prevent unauthorized persons from refilling the bottle.

With these and other objects in view, the invention consists of the novel combination and arrangement of parts which will be fully set forth in the following specification and accompanying drawings, in which,

Figure 1 is a longitudinal sectional view of a fragment of the bottle neck constructed in accordance with my invention, Fig. 2 is a transverse sectional view taken on the line 2—2 of Fig. 1, and, Fig. 3 is a view in elevation of a fragment of the bottle neck showing the same as it would appear in condition to be emptied.

Referring now to the drawings by characters of reference, the numeral 1 designates a bottle neck of the usual construction having formed at its upper end the enlargement 2. A suitable cap 3 is formed at the free terminal of the enlargement 2 and the point at which the cap 3 joins the enlargement is reduced as at 4 to permit the cap to be easily broken without injuring the remaining portion of the bottle. The usual stopper 5 is placed in the bottle neck. When the neck and cap are being formed said stopper is provided with the vertical aperture 6, the use of which will appear as in the preceding description. A similar aperture 7 is formed in the cap 3 and registers with the aperture 6 to form a passage

through which the filling stem or tube 8 extends.

The bottle is made so that the stopper 5 is placed in the neck when the same is molded and the filling tube 8 extended through the apertures hereinbefore described, so as to permit the bottle to be easily and quickly filled. After the filling process has been completed the stem 8 is withdrawn and the aperture sealed by pouring molten wax or any suitable substance into the said aperture 6. The aperture 7 in the glass cap is then sealed by heating and fusing the edges thereof together and the bottle may then be shipped to its destination. When it is desired to open the bottle the cap 3 is broken on the reduced portion 4 thus exposing the stopper 5 which may be withdrawn from its position in the bottle in any suitable manner, thus permitting the contents of the bottle to be removed. It will be apparent that should the contents of the bottle be tampered with in any way that the fact will be known since it is impossible to gain entrance to the interior of the bottle without breaking the cap from its position and thus danger of substitution will be eliminated.

Having thus described my invention I claim:

A non-refillable bottle including a neck, an enlargement formed at the free terminal of the neck, a cap formed at the free terminal of the enlargement and being joined thereto by a reduced portion, said cap being provided with a filling aperture and a stopper in the bottle neck and provided with an aperture adapted to register with the aperture with the cap to provide for the insertion of a filling tube.

In testimony whereof I affix my signature in presence of two witnesses.

HENRY C. BRAMKAMP.
